(57)

CLAIM

The ornamental design for a combination golf ball and marker, as shown and described.

DESCRIPTION

FIG. 1 is a perspective view of my new combination golf ball and marker;

FIG. 2 is a top view thereof;

FIG. 3 is a left side view thereof;

FIG. 4 is a right view thereof;

FIG. 5 is a back view thereof; and,

FIG. 6 is a bottom side view thereof.

The broken lines shown on the drawings form no part of the claimed design.
